UNITED STATES PATENT OFFICE

MICHAEL J. ULINE, OF TOLEDO, OHIO, ASSIGNOR TO GIFFORD-WOOD COMPANY, OF HUDSON, NEW YORK, A CORPORATION OF NEW YORK

ICE CONVEYER

Application filed July 28, 1926. Serial No. 125,390.

This invention relates generally to conveyers and more particularly to an ice conveyer for feeding the cakes of ice from the storage house or compartment to a platform 5 of the feed mechanism connected with an ice scoring machine. It will be distinctly understood that this improved conveyer can be employed in connection with any type of ice scoring machine and is preferably operated 10 from the same motor.

In ice storage houses or compartments as usually constructed the floor is of cork and approximately four feet in thickness. One of the objects of my invention, therefore, is 15 to provide a device the installation of which will necessitate the removal of the least quantity of cork and another object of the invention is to provide a conveyer which will have these advantageous characteristics and 20 which will feed the cake of ice sidewise instead of lengthwise as heretofore practiced so that more ice per lineal foot of the conveyer can be loaded upon the conveyer inside of the storage house or compartment.

25 With these objects in view and certain others which will be apparent as the description proceeds the invention consists in the novel features of construction and in the manner of combining or arranging the same 30 all of which will be fully described herein-after and set forth in the appended claims.

In the accompanying drawings forming a part of this specification, Fig. 1 is a top plan view of an ice conveyer embodying one form 35 of my invention; Fig. 2 is a sectional elevation taken at the forward end of the device; Fig. 3 is a similar view at the rear end of the device; Fig. 4 is a sectional elevation taken 40 at the forward end of the device at approximately right angles to the position shown in Fig. 2 and Fig. 5 is a transverse sectional view on the line 5—5 of Fig. 1.

45 Referring particularly to the drawings A indicates the floor of the storage house or compartment which is preferably made of cork or any other suitable insulating material and in said floor adjacent the exit there is provided a transverse pit B and at the proper distance from the pit B there is produced a second pit C but it will be noticed, by

comparing Figs. 2 and 3, that the pit C is much shallower than the pit B. The pits B and C are connected by means of a central channel-way D and side channel-ways E.

55 F indicates a platform which may be provided with any suitable type of feeding mechanism for carrying the cakes of ice to a scoring machine or elsewhere.

My improved construction of conveyer is intended to be arranged and operated within 60 the pits B and C and channelways D and E (Figs. 1 and 5) and in constructing this conveyer I employ two endless chains G, G traveling around sprockets H and I. The sprockets H are mounted upon shafts K 65 journaled in a bracket casting L which is formed with a suitable base and bolted to a foundation L' located in the bottom of the pit B. This casting L besides serving as bearings for the shafts K (which not only 70 carry the sprockets H but also the bevel gears N), provides suitable bearings for the shafts O carrying the bevel gears P which mesh with the bevel gears N. These shafts O also carry sprockets Q around which travels an endless chain Q' and upon the opposite 75 end of one of the shafts O there is also mounted a sprocket Q² around which travels the link chain Q³ receiving motion from a sprocket Q⁴ which may be mounted upon a 80 shaft Q⁵ extending from the ice scoring machine or any other suitable form of apparatus.

85 It will be noted that the bearings for the shafts K are inclined, these shafts converging upwardly as shown so that the sprockets H mounted upon the ends of said shafts will be inclined and will converge downwardly.

The sprockets I which are arranged in the pit C are mounted upon the ends of shafts K' 90 which are journaled in a casting L' secured to the floor and braced by means of rods L² connected to angle brackets L³ also secured to the floor and by means of which the casting L' can be adjusted back and forth so 95 as to compensate for any slack or adjustment necessary in the endless conveyer chains G which travel around the sprockets H and I. The shafts K' are inclined to correspond with the shafts K so that the sprockets I will con- 100

verge downwardly the same as the sprockets H.

The conveyer chains are provided at definite intervals with upwardly projecting ice-feeding pins or flights R, and in practice I prefer to arrange channel-ways E' in the side channels E and a centrally disposed channel-way D' in the central channel D and in which the lower, inner runs of the endless chains travel.

At the exit end of the conveyer the plate S is arranged, said plate being slotted from each side inwardly as indicated at S' and is also formed with a central depending rib or flange S². At each side there is also arranged a channel portion S³ corresponding with the channel-ways D'.

The sprockets are driven in such direction that the ice-feeding flights carried by the outer runs will move forwardly and these same flights during the return of the chain will of course move rearwardly. By virtue of the inclination of the sprockets, the ice-feeding flights of the outer runs will project above the horizontal plane of the plate S and on their return movements will be carried below this horizontal plane and therefore will not interfere with the cakes of ice which are being fed along the channel-ways and across the exit plates at the exit end of the conveyer.

By feeding the ice cakes sidewise instead of lengthwise as heretofore a larger number of cakes can be fed along by the conveyer at the same time; and by having the feeding flights arranged upon the outer runs of the chains, the contact with the cake of ice will be at spaced points and adjacent the ends; and as before stated, owing to the oblique positions of the sprockets and chains the return runs and flights connected thereto will be carried beneath the outwardly moving cakes of ice and not interfere therewith.

It will thus be seen that I provide an exceedingly simple and efficient construction of ice conveyer which will call for the least amount of insulation removal and which, owing to its peculiarities of construction, can be utilized to move the cakes of ice sidewise and whereby a larger number of cakes can be conveyed from storage with a given length of conveyer.

Obviously, the present invention is not restricted to the particular embodiment thereof herein shown and described.

Having thus described my invention, what I claim is:

1. In a device of the kind described, a pair of endless conveyer chains provided with upwardly projecting ice engaging means, sprockets around which said chains travel, said sprockets being inclined and having their adjacent edges converging downwardly, said sprockets being so moved that the ice engaging means carried by the outer runs

of the conveyer chains will project above a given horizontal plane and will be carried below said horizontal plane upon the return movements of said runs.

2. In a device of the kind described, the combination with two spaced brackets, of a pair of sprockets carried by each of said brackets, means for actuating said sprockets, the sprockets of each pair being inclined so that their adjacent edges converge downwardly, a pair of endless chains traveling around said sprockets, said chains having upwardly projecting ice engaging flights, and a channel-way in which both the lower runs of the chains travel.

3. In a device of the kind described, the combination with two spaced brackets, of a pair of sprockets carried by each of said brackets, means carried by one bracket for actuating the sprockets thereon, the sprockets of each pair being inclined so that their adjacent edges converge downwardly, endless chains traveling around said sprockets, said chains having upwardly projecting ice engaging flights arranged at spaced points, central and side channel-ways in which the runs of the chains travel, said flights projecting above the horizontal plane while moving through the side channel-ways and being wholly below said horizontal plane while traveling through the central channel-way.

4. In a device of the kind described, the combination with two spaced brackets, of a pair of sprockets carried by each of said brackets, means carried by one bracket for actuating the sprockets thereon, the sprockets of each pair being inclined so that their adjacent edges converge downwardly, a pair of endless chains traveling around said sprockets, said chains having upwardly projecting ice engaging flights arranged at definite points, side channel-ways and a central channel-way in which the runs of the chains travel, the flights projecting above a horizontal plane while the chains travel in the side channel-ways and below said horizontal plane when the runs of said chains travel in the central channel-way, and a plate arranged at the exit end of the conveyer, said plate being slotted to permit the movement of the ice feeding flights.

5. In a device of the kind described, the combination with a bracket having horizontal shafts journaled therein, said horizontal shafts carrying bevel gears and sprockets, inclined shafts also mounted in said bracket, said inclined shafts carrying bevel gears at their lower ends and sprocket wheels upon their upper ends, a second bracket having inclined shafts journaled therein, said inclined shafts having sprocket wheels upon their lower ends, endless chains traveling around said sprockets, said chains being provided with upwardly projecting ice

engaging pins, channel-ways in which the runs of the chain travel, a plate at the exit end of the conveyer, said plate being slotted to permit the movement of the ice-feeding pins, the second named bracket being adjustable, the chain conveyer sprockets being so inclined that the ice-feeding pins carried by the feeding runs of said chains will project above a horizontal plane and be carried below said plane upon the return movement of said runs.

6. In a device of the kind described, a plate upon which a cake of ice can move, a pair of endless chains for moving said cake of ice, sprockets around which said chains travel, inclined shafts carrying said sprockets and so positioned that the adjacent edges of said sprockets converge downwardly, ice engaging means carried by said chains, said ice engaging means projecting above the plate when moving in one direction and beneath said plate when moving in the opposite direction, the remote runs of said pair of chains moving in one direction and the adjacent runs of said pair of chains moving in the opposite direction and beneath the plate.

7. A conveyer for ice cakes and the like comprising an endless chain; spaced sprockets about which the chain is trained; said chain having a plurality of upwardly projecting ice engaging flights; the axes of the sprockets being inclined relative to the vertical so that the entire chain conveyer runs in a plane inclined relative to a horizontal floor and has one run below the floor and the other run with the flights above the floor, the top and ends of the conveyer being so arranged that ice cakes may be passed on the receiving end of the conveyer and off the discharging end of the conveyer without interference from the flights; and means for driving one of the sprockets to run the conveyer.

In testimony whereof, I hereunto affix my signature.

MICHIEL J. ULINE.
